UNITED STATES PATENT OFFICE.

WILLIAM F. MOON, OF MILWAUKEE, WISCONSIN.

YARN-SPECK REMOVER.

1,334,669.

Specification of Letters Patent. Patented Mar. 23, 1920.

Application filed November 24, 1919. Serial No. 340,211.

To all whom it may concern:

Be it known that I, WILLIAM F. Moon, a citizen of the United States, and resident of Milwaukee, in the county of Milwaukee, and State of Wisconsin, have invented new and useful Improvements in Yarn-Speck Removers, of which the following is a description, reference being had to the accompanying drawings, which are a part of this specification.

The present invention relates to a device for removing lumps of fiber or what are commonly termed "specks" from yarn or thread, previous to its use in a spinning or weaving machine.

One object of this invention is to provide a device of this character which will include rotating members for crushing or severing the speck from the thread.

Another object of the present invention is to provide a device of this character which will have revoluble and yieldable means coöperating with a speck positioning member to crush or sever the speck from the thread or yarn.

A further object of this invention is to provide a device of this character having a revoluble speck positioning member, and a revoluble crushing wheel yieldingly held in engagement therewith whereby friction is reduced to a minimum.

With the above and other objects in view which will appear as the description proceeds, my invention resides in the novel construction, combination and arrangement of parts, substantially as hereinafter described and more particularly defined by the appended claims, it being understood that such changes in the precise embodiment of the hereindisclosed invention may be made as come within the scope of the claims.

In the accompanying drawing I have illustrated one complete example of the physical embodiment of my invention constructed according to the best mode I have so far devised for the practical application of the principles thereof, and in which:

Figure 1 is a side view of a yarn speck remover embodying the principles of my invention, said view having parts broken away and in section to more clearly illustrate details of construction.

Fig. 2 is a view, part in section and part in elevation, said view being taken on the line 2—2 of Fig. 1.

Fig. 3 is a side view of a slightly modified

form of my invention, said view having parts broken away and in section, and

Fig. 4 is a view, part in section and part in elevation, said view being taken on the line 4—4 of Fig. 3.

Referring now to the drawings, and more particularly to Figs. 1 and 2, the numeral 5 designates generally the frame of my machine which has a plurality of pairs of opposed upwardly extending arms 6 rigid with the frame.

In the drawing, I have illustrated a plurality of speck removing devices carried by the frame 5, each of which successively acts upon the thread or yarn to remove any specks thereon, so that if the first device does not remove the speck it will be removed by another of the devices.

Each of these speck removing devices is disposed between the adjacent pair of arms 6, and consist generally in means for presenting the speck in a position in which it may be readily severed from the thread or yarn by means coöperating with the speck positioning means, as hereinafter described.

The means for presenting the speck in position to either side consists of a revoluble bed block 7 rotatably mounted in the frame 5 intermediate each opposed pair of arms 6 by means of journals 8 and 9, as best shown in Fig. 2. The bed block 7 is in the shape of a roll and coacts with the crushing or severing means, to be later described, to remove the specks from the yarn or thread 10 as it is guided through the frame. The yarn or thread 10 is guided through the frame 5 by suitable guiding members 11 and 12, located at each end of the frame, and the thread in its passage through the frame engages the top of the bed block, and should the speck be on the under side of the yarn or thread, the same will be turned or positioned to one side, there to be severed or crushed from the yarn or thread by the coöperating means, as will be later described.

As the bed block 7 is insufficient in itself to properly retain the thread upon its top surface, in that the thread would possibly become disengaged therefrom, I so construct my severing or crushing means as to be constantly in yielding engagement with the bed block to provide what may be termed a guide channel for the thread or yarn as it passes over each bed block. The severing or crushing means consist of a pair of rev-

oluble crushing or cutting wheels 13 carried by the adjacent pair of arms 6 and having their crushing or severing edges at all times yieldingly held in engagement with 5 the adjacent bed block 7.

The upper end of each arm 6 is formed 10 with a cylinder or centrally apertured cap 14, in which is slidably mounted a hollow sleeve end 15 of a retaining block 16. Mounted within the hollow of the sleeve 15 is an extensible spring 17 having its upper 15 end bearing against a plate 18 disposed within the aperture of the cap 14 and carried by a tension adjusting screw 19. One crushing or cutting wheel 13 is rotatably secured to the inner face of each retaining block 16 by means of a journal 20 and has its crushing or severing edge yieldingly held in engagement with the adjacent bed block 7 by means of the spring 17.

The wheels 13 of each pair are spaced apart a distance substantially equal to the thickness of the thread or yarn being cleaned as it is guided through the frame, 20 between the wheels of each pair, by the guiding members 11 and 12, and the speck, if on the underside of the thread or yarn, will be positioned to one side and severed or crushed from the thread or yarn by the operating bed block 7 and the wheels 13, 30 which are rotated by the means now about to be described.

The journals 9 of the bed blocks 7 are projected outwardly of the frame 5 and have worm gears 21 secured thereto, which worm gears are in mesh with worms 22 formed on a drive shaft 23 journaled in the adjacent side of the frame. The shaft 23 is rotated by any desired means and in the present instance I have illustrated the same as connected with a pulley 24, connected with a suitable source of power (not shown), by a gear pinion 25 fixed to the shaft 23 and in mesh with a gear pinion 26 fixed to the 40 shaft 27 of the pulley 24.

The bed block 7 of each speck removing device is thus rotated in the direction of arrow 28, see Fig. 1, and the crushing or cutting wheels 13 are also rotated in the direction of arrow 29 by reason of their engagement with the adjacent bed block. With this structure, the speck as it is positioned to the side is engaged between the bed blocks and the crushing or cutting wheels 50 and removed from the thread or yarn up close thereto by reason of the wheels 13 of each pair being spaced apart a distance only equal to the thickness of the thread. In this manner the thread or yarn is thoroughly cleaned and if a speck is skipped by one device it is removed by another.

In that form of my invention depicted in Figs. 3 and 4, the arms 6 are each formed at their upper ends with a bearing portion 60 30 projecting inwardly over the adjacent

bed block 7. In this instance the bed blocks are journaled in a sliding block or retainer 31 mounted in the frame 5 and normally yieldingly urged upwardly by means of a tension spring 32, and the crushing or cutting wheels 13 are splined to the portion of the shafts 33 disposed between the adjacent bearings 30 by a key member 34.

The wheels 13 of each pair are held in spaced relation by means of a spacing collar 35 and have their crushing or severing edges at all times in engagement with the adjacent bed block 7, as in that form of my invention depicted in Figs. 1 and 2. The yielding engagement between the wheels 13 and bed blocks 7 is adjustable by means of the adjusting screws 36, see Fig. 4.

In this form of my invention the wheels 13 are positively rotated by the shaft 23, the worms 22 of which mesh with worm 85 gears 37 fixed to one end of shafts 33, and the bed blocks 7 are rotated by reason of their frictional engagement with the wheels 13. The direction of rotation of the wheels 13 and bed block 7 is as indicated by arrows 38 and 39 respectively, see Fig. 3, and as the operation of this form of my invention is identical with that form of my invention depicted in Figs. 1 and 2, further description is thought unnecessary.

From the foregoing description, taken in connection with the accompanying drawing, it will be at once apparent that I provide means for positively cleaning or removing specks from thread or yarn prior to its use 100 in a spinning or weaving machine.

What I claim for my invention is:

1. A yarn speck remover comprising revoluble means for positioning the speck, revoluble means coöperating with the first 105 mentioned means for detaching the speck from the yarn, adjustable means for yieldingly urging the peripheries of said revoluble means into engagement, and means for rotating said revoluble means.

2. A yarn speck remover comprising means for guiding a thread, a plurality of rotatable bed blocks adapted to turn the thread to bring a speck thereon to one side, and a plurality of rotatable members co- 115 operating with the bed blocks to detach the speck from the thread as it is guided therethrough.

3. A yarn speck remover comprising a rotatably mounted bed block over which a 120 thread is guided, and a crushing wheel engaging said bed block and coöperating therewith to crush specks from the thread.

4. A yarn speck remover comprising a rotatably mounted bed block over which 125 a thread is guided, a crushing wheel having its periphery in frictional engagement with said bed block and coöperating therewith to remove specks from the thread, and means for rotating the bed block.

5. A yarn speck remover comprising a rotatably mounted bed block over which a thread is guided, a crushing wheel, means 45 yieldingly urging the periphery of the crushing wheel to frictionally engage the periphery of the bed block, said crushing wheel coöperating with the bed block to remove specks from the thread as it is guided thereover, and means for rotating the bed 50 block.

10 6. A yarn speck remover comprising a rotatably mounted bed block over which the thread is guided, an adjustably mounted member juxtaposed the bed block, a crushing wheel revolvably carried by said adjustable member toward the bed block whereby the periphery of the crushing wheel is yieldingly maintained in frictional engagement with the periphery of the bed block so that 15 the bed block and crushing wheel coöperate in removing specks from the thread as it is guided over the bed block, and means for rotating said bed block and crushing wheel.

20 7. A yarn speck remover comprising a rotatably mounted bed block over which a thread is guided, an arm mounted adjacent the bed block and having a portion disposed over the bed block, a retaining block having a portion slidably mounted in the 25 portion of the arm disposed over the bed block, a crushing wheel carried by said retaining block, means yieldingly urging the crushing wheel to engagement with the bed block, and means for rotating said bed block 30 and crushing wheel.

35 8. A yarn speck remover comprising a frame, means for guiding a thread through the frame, and a plurality of speck removing devices for removing specks from the 40 thread as it is guided through the frame, each speck removing device consisting of a bed block rotatably mounted in the frame,

a pair of arms disposed one on each side of the bed block and each having a portion disposed over the bed block, a pair of crushing wheels carried by said arms and urged to engagement with the bed block, said crushing wheels being spaced apart a distance substantially equal to the thickness of the thread being operated upon and the 45 thread being guided over the bed block between the crushing wheels, and means for rotating the crushing wheels and the bed block.

50 9. A yarn speck remover comprising a frame, means for guiding a thread through the frame, and a plurality of speck removing devices for removing specks from the thread as it is guided therethrough, each speck removing device consisting of a bed 55 block journaled in the frame and having one end extended outwardly of the frame, means engaging the extended end of the bed block for rotating the same, a pair of arms disposed one on each side of the bed block, 60 an apertured cap portion formed on the outer end of each arm and disposed over the bed block, a retaining block carried by each arm and having a portion mounted within the aperture of said cap portion, a 65 crushing wheel rotatably carried by each retaining block and means contained within the apertured cap portion of each arm for urging the crushing wheels to engagement with the bed block, the thread being guided 70 over the bed block between the crushing wheels and said crushing wheels being spaced apart a distance substantially equal to the thickness of the thread being operated upon and being rotated by reason of 75 their engagement with the bed block.

In testimony whereof I affix my signature.

WILLIAM F. MOON.
